L. G. HURD,
DUCK DECOY,
FILED AUG. 30, 1920.

WITNESSES:

Chas A. Lawson
Charles A. Hopkins.

INVENTOR:

Leigh G. Hurd.
By Leigh G. Hurd.

UNITED STATES PATENT OFFICE.

LEIGH G. HURD, OF LOS ANGELES, CALIFORNIA.

DUCK DECOY.

Application filed August 30, 1920. Serial No. 406,791.

To all whom it may concern:

Be it known that I, LEIGH G. HURD, a citizen of the United States, residing at Los Angeles, in the county of Los Angeles 5 and State of California, have invented new and useful Improvements in Duck Decoys, of which the following is a specification.

My invention relates to improvements in duck decoys, and particularly to decoys of simple construction and that can be assembled and taken apart very quickly. Another object is to provide a decoy that will take up a very small amount of space when taken apart and being carried.

15 A further object is to provide a decoy that will be almost impossible to get out of order and be of a very substantial construction. A still further object of my invention is to provide a decoy very life 20 like in appearance. Other objects will appear hereinafter.

My invention is illustrated in the accompanying drawings in which:

Figure 1 is a side elevational view of the 25 decoy assembled ready for use, and is the preferred form of my invention. Figure 2, is a side elevational view of the front end of the decoy body, showing the L shaped lug for attaching to the removable adjustable 30 head. Figure 3, is a bottom view of the removable adjustable head. Figure 4, is a perspective view of the projecting member which is attached permanently to the detachable floating bottom. Figure 5, is an end 35 view of the detachable floating bottom. Figure 6, is a front view of the hollow body. Figure 7, is a perspective view of the spring fastener or clip that is attached permanently to the hollow body. Figure 8, is a 40 front elevational view of a modified form of the hollow body. Figure 9, is a top view of the detachable floating bottom on which the decoy body is mounted. Fig. 45 10 is a top view of the front end of the detachable floating bottom showing the modified form.

Similar numerals refer to similar parts throughout the different views. Referring to the drawings, 3 indicates the hollow body 50 of the decoy which is preferably made from stamped sheet metal, the bottom part being open so that the body can be attached to the detachable floating bottom 13, and also for the purpose of nesting the bodies together 55 when taken apart for carrying purposes. When taken apart the bodies 3 of the de-

coys are nested together, and the heads 2 are placed inside of the bodies. The detachable floating bottoms 13 are placed together, taking up very little room. 60

The removable adjustable head 2 can either be made from solid wood or sheet metal as preferred. The detachable floating bottom 13 is preferably made from wood, but can be made from any other material 65 that will float. The L shaped lug 8 is attached permanently to the top front end of the hollow body, as shown in Figures 2, 6 and 8. The base 9 of the removable adjustable head 2, shown in Figures 1 and 3, has 70 an opening or orifice 10 in the center of the same, into which the L shaped lug 8 fits when in the correct position. The base 9 is attached permanently to the bottom part of the head 2 as shown by the dotted lines 75 at 9 in Figure 1. If the head 2 is made of solid wood or other solid material the neck will have to be hollowed out sufficiently to receive the base 9. This will of course not be necessary if a sheet metal head is used. 80 In the preferred construction of the head, it is made from sheet metal as shown in the drawing, so therefore does not have to be hollowed out, as would be the case if a solid head was used. The thickness of the neck 85 base 9 should be the same as the distance between the projection of the L shaped lug and the top of the decoy body adjacent the L shaped lug.

The projecting member 4, shown in Figure 4 to be inserted in the orifice 12, is preferably made of brass or other metal that will not rust, and has a hole in front end of the same for inserting the anchor cord 6 as shown at 19 in Figures 1, 9 and 4. The 95 weight 7 is attached to the cord 6.

The projecting member 4 is attached permanently to the detachable floating bottom 13 by screws or other means inserted in the holes 11 as shown in Figure 4. The spring 100 fastener or clip 5, shown in Figure 7 to be inserted in the orifice or slot 17 shown in Figure 5, is attached permanently to the hollow body 3 by means of a screw, rivet or other means being inserted thru the hole 105 21, as shown in Figure 7. In attaching the fastener or clip 5 to the hollow body 3, it is placed on the opposite side from the orifice 12 shown in Figure 6, or the orifices 14 shown in Figure 8. In Figure 5 a metal 110 plate 16 is attached permanently to the detachable floating bottom 13, by means of

screws or nails being inserted thru the holes 18. This plate 16 has a slot or opening 17 which is intended to receive the fastener 5 when the hollow body 3 is mounted on the 5 detachable floating bottom 13. The metal plate 16 is attached to the detachable floating bottom 13 on the opposite side from the projecting member 4 as shown in Figure 9. In Figure 9, 20 shows the location of the 10 screws which holds the plate 16 in place. The lines 15 in Figure 10 show the location of the two projecting members 15. In using this construction the projecting member 4 would not be attached to the detachable 15 floating bottom at all, the two projecting members 15 taking the place of the same. In using this construction the weight 7 with the cord 6 attached would have to be attached to the floating bottom by using an 20 ordinary screw eye or ring attached to the bottom front end of the floating bottom 13.

In the operation of the decoy, the projecting member 4, is inserted in the orifice 12 in the hollow body 3, adjacent its open under 25 side as shown in Figure 6. The body 3 of the decoy is then pressed down on the detachable floating bottom 13 until the fastener or clip 5 slips automatically into the slot 17 in the plate 16 on the detachable floating 30 bottom 13. This detachably secures the hollow body 3 to the detachable floating bottom 13.

In the modified form of my invention, 35 two projecting members 15 are permanently attached to the detachable floating bottom 13 as shown in Figure 10 at 15. In using this construction the projecting member 4 is eliminated, the two projecting members taking its place. In this construction the operation 40 of the decoy is the same as when only one projecting member 4 is used, as the projecting members 15 are inserted in the orifices 14 adjacent the open under side of the hollow body 3 as shown in Figure 8. After 45 the projecting members 15 are inserted in the orifices 14 in the hollow body 3, the body 3 is pressed down on the detachable floating bottom 13 until the fastener 5 slips into the slot 17, which detachably secures the hollow 50 body 3 to the detachable floating bottom 13. After the hollow body 3 is attached to the detachable floating bottom 13, the removable 55 adjustable head 2 is positioned on the top front end of the hollow body 3 with the bill of the decoy pointing towards the rear, if the orifice 10 in the neck base 9 is in the same position as shown in the drawing, although the position of the orifice 10 in the neck base 9 can be changed if desired without departing from the spirit of my invention. The position of the orifice 10 in the neck base 9 as shown in the drawing is the preferred position for receiving the L-shaped lug 8. In this position as shown in the

65 drawing the L-shaped lug 8 will fit into the orifice 10 in the "neck base" 9. Turning the head 2 a fraction of a turn either to the right or the left will securely lock the head 2 to the hollow body 3 as can readily be seen. When taking the decoy apart all that is necessary, is to pull the fastener 5 out of the slot 17 when the decoy can be quickly taken apart the same way it was assembled.

70 It can readily be seen that this decoy possesses all the advantages of the solid wooden and collapsible decoys, but that it does not possess their disadvantages.

75 Having thus described my invention, what I claim is:

1. A decoy comprising the combination of 80 a hollow body with the bottom part open, a removable head, a detachable floating bottom having an orifice for receiving a fastener which is attached to the hollow body adjacent its open under side, and which co-operates with means on the opposite side of the decoy in detachably securing the hollow body to the detachable floating bottom.

2. A decoy comprising the combination of 85 a hollow body with the bottom part open, a removable head, a detachable floating bottom permanently equipped with a projecting member which fits into an orifice in the hollow body adjacent its open under side, and an orifice in the detachable floating bottom 95 diametrically opposite the projecting member, which receives a fastener attached to the hollow body adjacent its open under side, and which detachably secures the hollow body to the detachable floating bottom.

100 3. A decoy comprising the combination of a hollow body with the bottom part open, a removable head, a detachable floating bottom equipped permanently with a projecting member for inserting in an orifice in the hollow body adjacent its open under side, and an orifice in the detachable floating bottom opposite the projecting member for receiving fastening means which is attached to the hollow body adjacent its open under side, and which detachably secures the hollow body to the detachable floating bottom.

110 4. A decoy comprising the combination of a hollow body with the bottom part open, a removable head, a detachable floating bottom 115 permanently equipped with projecting members for inserting in openings in the hollow body adjacent its open under side, and an orifice in the detachable floating bottom 120 positioned opposite the projecting members which receives a projecting member attached to the hollow body adjacent its open under side, and which detachably secures the hollow body to the detachable floating bottom.

125 In testimony whereof I have signed my name to this specification.

LEIGH G. HURD.
